INVENTOR:

D. W. Richards,
BY A. Z. Vencill

His ATTORNEY

UNITED STATES PATENT OFFICE.

DANIEL W. RICHARDS, OF ROANOKE, VIRGINIA.

CIRCUIT CONTROLLER.

Application filed October 2, 1922. Serial No. 591,727.

To all whom it may concern:

Be it known that I, DANIEL W. RICHARDS, a citizen of the United States, residing at Roanoke, in the county of Roanoke and State of Virginia, have invented certain new and useful Improvements in Circuit Controllers, of which the following is a specification.

My invention relates to electrical circuit controllers.

I will describe one form of circuit controller embodying my invention, and will then point out the novel features thereof in the claim.

15 In the accompanying drawings, Fig. 1 is a view showing, in front elevation, one form of circuit controller embodying my invention. Fig. 2 is a plan view of the circuit controller shown in Fig. 1. Fig. 3 is 20 a fragmental view showing the disposition of the contact parts when the circuit controller shown in Fig. 1 is closed.

Similar reference characters refer to similar parts in each of the three views.

25 Referring first to Figs. 1 and 2, the circuit controller comprises a base plate A of some suitable insulating material such as micarta, upon which base plate the various parts of the circuit controller are mounted.

30 The external circuit is controlled by means of a bridging contact member C, operated by certain mechanism which is described in detail hereinafter, and coacting with two contact arms B. Two contact supports E are

35 spaced from each other and fastened by means of screws 2 to the base plate A in such positions that they are substantially parallel with respect to each other and to the longitudinal axis of the base plate. One end of 40 each such support extends beyond the edge of the base plate and is provided with a screw 3 and a washer 4 for connection to the external circuit. Each of these contact supports is provided with two upstanding ears 5

45 which carry a pivot pin 6. Mounted to rock on this pivot pin is a metallic contact arm B having two upstanding ears 8 through which the pivot pin 6 passes. The two supporting ears on the arm B are interposed 50 between the two ears on the contact support as shown in Fig. 2. Near its right end each contact arm B carries a ferrule 10 which is provided with a graphite contact button 9. The contact arm B is biased to the position 55 shown in Fig. 1 with relation to the contact support E by means of a spring 12 which

surrounds a screw 11 mounted in the contact support E. The lower end of the spring 12 bears upon the left hand side of the arm B whereas the upper end of the 60 spring 12 bears against a nut 13 on the screw 11. A lock nut 14 serves to retain the nut 13 in its adjusted position on screw 14. The screw 11 is threaded into a suitable hole in the contact support E and passes freely 65 through a hole in arm B. A flexible lead 33 connects the arm B to the support E so as to provide a path for electrical current from screw 3 to contact button 9 through support E, conductor 33 and arm B. 70

The mechanism for operating the bridging contact member C is mounted on a supporting member D. This member is fixed to the base plate A and comprises a flat bottom plate 15 having two upstanding 75 posts 16 provided with triangular recesses at their tops to accommodate the knife edges of two sheet metal members J and H. A pin 40 passes through these two posts and extends between them. This bottom plate is 80 also provided with a pair of upstanding lugs 17 having a pin 19 upon which is pivotally mounted a latching member G shaped substantially as shown in the drawings. The bottom plate is also provided with an up- 85 standing lip 18. A wire coil spring 31, fastened at one end to the lip 18 and at the other to the latch member G, normally biases this member to the left, as shown in Fig. 1.

The member H is of irregular shape and 90 comprises two legs 34 having knife edges 27 on their ends which knife edges are inserted in the triangular recesses in the post 16. The member H also comprises a tongue 24, two outstanding ears 35 and two retroflexed 95 arms 36. Riveted to the end of each such arm is a flat spring 25 which extends back along the arm past the bend. Supported by the free ends of the two springs 25 is the bridging contact member C which comprises 100 a flat bar of some suitable conducting material, such as nickel-plated copper, provided with contact plates of silver on the lower side of its two ends and is so disposed as to make contact with the two carbon buttons 105 9 when the member H is moved downward about its knife edges 27. The upstanding portion of the latch G passes through a slot in the member H and is provided with a shoulder 23 to limit the upward motion of 110 member H.

The trigger member J comprises a flat

plate having two projecting ears 37, a tongue 26 which engages with the arm 20 of latch G, two receding claws 38 which are bent around the pin 40 but spaced therefrom, and 5 two eyes 29 to which are fastened means for operating the circuit controller. These means are not essential to the complete disclosure of my invention and have been omitted from the drawings for the sake of 10 simplicity.

15 A wire coil spring 30 has one end fastened to one of the ears 35 on member H and its other end to the associated ear 37 on trigger J. A similar spring 30 is fastened between 15 the two ears 35 and 37 on the other side of the device.

20 The operation of the circuit controller is as follows: As shown in Figs. 1 and 2, the circuit controller is open. Now if the right- 20 hand end of trigger J is moved downwardly, no motion of the member H will result until the plane defined by the points of connection of the two springs 30 passes below the 25 knife edges 27 and 28. In this position the springs 30 will have a downwardly directed vertical component of force which will pull the member H downwards, thus moving the bridging member C downward against the contact buttons 9. But this action causes 30 the vertical component of the force exerted by the springs 30 to be increased and the result is that the closing of the contact is a quick action. When the member C comes 35 in contact with the buttons 9, the springs 25 are flexed, moving the tongue 24 into contact with the bridging member C and allowing the shoulder 22 on latch G to engage the slot in the member H. Since the tongue 26 on trigger J has been moved out of engagement 40 with arm 20 on latch G by the actuating motion referred to above, it is clear that the spring 31 will draw the top of latch G toward the left, thus securing the controller in this position until released. When 45 the bridging member C comes in contact

with the buttons 9 it forces the arms B to swing about their pivots 6 till they assume the position shown in Fig. 3. Thus it is clear that when the circuit controller is 50 closed the contact buttons 9 and the bridging member are forced together by the combined action of the springs 12 and the springs 30 and are held in this position by means of the latch G coacting with member 55 H.

When the right-hand end of trigger J is again raised, no motion of member H can take place till arm 20 of latch G has been engaged by tongue 26 on trigger J. When the trigger J is tipped so far as to engage 60 this arm the force exerted by the springs 30 has a large upwardly directed vertical component so that as soon as latch point 22 is disengaged from the slot edge of member H, this member moves sharply upward opening 65 suddenly the contacts between bridging member C and contact buttons 9. The member H continues to move upward till it engages shoulder 23 on latch G and in this position the circuit controller is open. 70

Although I have herein shown and described only one form of electrical circuit controller embodying my invention, it is understood that various changes and modifications may be made therein within the 75 scope of the appended claim without departing from the spirit and scope of my invention.

Having thus described my invention, what I claim is:

A circuit controller comprising a sheet metal member having two arms, a projecting tongue, two flat springs each having one end riveted to the tip of one arm and the other end to a bridging contact member, two contact arms, and means for moving said bridging member into and out of engagement with said arms. 85

In testimony whereof I affix my signature.
DANIEL W. RICHARDS.
